No. 625,209.

Patented May 16, 1899.

E. E. STEAR.
BRACE WRENCH.

(Application filed Jan. 28, 1899.)

(No Model.)

UNITED STATES PATENT OFFICE.

ELMER E. STEAR, OF MILLSTONE, PENNSYLVANIA.

BRACE-WRENCH.

SPECIFICATION forming part of Letters Patent No. 625,209, dated May 16, 1899.

Application filed January 28, 1899. Serial No. 703,727. (No model.)

To all whom it may concern:

Be it known that I, ELMER E. STEAR, a citizen of the United States, residing at Millstone, in the county of Elk and State of Pennsylvania, have invented certain new and useful Improvements in Adjustable Brace-Wrenches; and I do hereby declare the following to be a full, clear, and exact description of the invention, such as will enable others skilled in the art to which it appertains to make and use the same.

This invention relates to wrenches of the sliding-jaw class; and the object of the same is to provide a device of this character with an interdependent brace member to effectively operate it, and whereby a continuous, rapid, and forceful means is attained for applying and removing nuts of varying shapes and sizes and dispensing with the use of independent wrenches of different sizes.

The invention consists of the construction and arrangement of parts hereinafter more fully described and claimed.

In the accompanying drawings, Figure 1 is a side elevation of a wrench embodying the invention. Fig. 2 is a bottom plan view of the same partially broken away.

Referring to the drawings, wherein similar numerals are utilized to indicate corresponding parts in the views, the numeral 1 designates the brace member, having a swiveled head or analogous device 2 to rest in the hand or against the chest of the operator, a stock 3 and a crank 4 with a grip 5, all of said parts representing in combination a construction substantially like the ordinary boring-brace.

The invention resides in the partial continuity only of the crank 4 and the fixed addition thereto of an angle-arm 6, extending from the inner termination of a stationary wrench member 7, having a substantially V-shaped jaw 8 on the lower portion of the outer termination and an apertured guide 9 in rear of said jaw. By means of the guide 9 a movable wrench member 10 is held in relative position to the stationary wrench member, and has an outer head 11, also provided with a substantially V-shaped jaw 12 to coact with the jaw 8 in grasping and holding a nut. The shank 13 of said wrench member 10 is

preferably rounded and screw threaded, as at 14, and is adjustable through a smooth opening 15 in the vertical part of the angle-arm 6, adjacent the meeting-point thereof with the stationary wrench member. This opening 15 also extends through an integral collar 15^a at the rear of the angle-arm 6. On the part of the shank 13 in rear of the vertical part of the angle-arm a screw-sleeve 16, having a roughened or milled head 17, is adjustably mounted and is recessed at the front to fit over the rear end of said collar 15^a, and between the front end of said sleeve and the adjacent part of the arm 6 a spring-washer 18 surrounds said collar and is split for application and clamping purposes.

In operation the stationary wrench member 7 has its jaw 8 placed against one portion of the nut, and the movable wrench member 10 has its jaw 12 fitted against an opposite part of the nut. To primarily arrange the jaw of the movable wrench member against the nut, said member is pushed away from or drawn toward the jaw 8 of the member 7, which can be readily accomplished by drawing or pushing the shank through the opening 15 in the angle-arm. After the two jaws are applied to the nut they can be easily tightened by adjusting the sleeve 16 to cause the front end thereof to bear against the washer 18 and force the latter into close engagement with the angle-arm 6, and thereby immovably bind the parts. The nut can now be quickly removed or applied by rotating the crank 4, which correspondingly revolves the wrench members while the swiveled head 2 is held by or against the person of the operator. By loosening the sleeve 16 or running it back on the shank 13 the movable wrench member 10 can be pushed out to move its jaw 12 away from the jaw 8 and disengage the device as an entirety, and in said operations the washer 18 always remains seated on the collar 15^a.

The wrench set forth is exceptionally convenient for taking off and putting on the burs of buggy and carriage axles when oiling or greasing the spindles thereto, as it will fit different-sized burs and in the event of removal hold them in the socket formed by the jaws 8 and 12 until they are replaced on the spindles, thus preventing dirt and grease

from getting on the hands of the operator, which usually results by the use of different kinds of wrenches.

Changes in the proportions, dimensions, 5 and minor details could be made to accommodate variations in the size of device without departing from the nature or spirit of the invention.

Having thus described the invention, what 10 is claimed as new is—

In a wrench of the character set forth, the combination of a brace, a stationary wrench member rigidly connected to the crank of said brace by an angle-arm and having a 15 jaw thereon, the said angle-arm having an unthreaded opening extending therethrough and an integral rearwardly-projecting collar through which said opening is continued, an

adjustable wrench member bearing against the stationary wrench member and having a 20 screw-threaded shank freely movable through the opening in said angle-arm and collar thereon, and also having a jaw, a screw-sleeve having a roughened or milled head engaging the rear portion of the screw-shank of 25 the adjustable wrench member, and a split spring-washer in rear of the angle-arm and engaging the collar thereof, said washer being interposed between the front end of the screw-sleeve and said arm. 30

In testimony whereof I affix my signature in presence of two witnesses.

ELMER E. STEAR. [L. S.]
